UNITED STATES PATENT OFFICE.

HENRY O. THOMAS, OF FREMONT, NEBRASKA.

BEDCLOTHES-HOLDER.

SPECIFICATION forming part of Letters Patent No. 351,411, dated October 26, 1886.

Application filed February 11, 1886. Serial No. 191,540. (No model.)

To all whom it may concern:

Be it known that I, HENRY O. THOMAS, of Fremont, in the county of Dodge and State of Nebraska, have invented certain new and useful Improvements in Bedclothes-Holders; and

5 I do hereby declare the following to be a full, clear, and exact description of the invention, such as will enable others skilled in the art to which it appertains to make and use the same.

10 My invention relates to an improvement in bedclothes-holders.

The object is to provide a simple, efficient, and inexpensive device for holding bedclothes on the bed against displacement.

15 With these ends in view my invention consists in certain features of construction and combinations of parts, as will be hereinafter more fully described, and pointed out in the claims.

20 In the accompanying drawings, Figure 1 is a vertical longitudinal section of a bed, showing the coverings in position in the holder; Fig. 2, a view in elevation of the foot-board, showing the holder applied thereto. Fig. 3 is 25 a modification.

A represents a panel of the foot-board, to which the base B of the holder is secured; or the base B might be secured to a beam or cross-slat, B', or to a standard, B'', (shown in dotted lines, Fig. 2,) located at the foot or other part of the bed where it is desirable to have the clothes held. The base B is conveniently secured to the panel A or other support by screws b; but it may be satisfactorily 35 secured in numerous other ways.

To the base B is hinged a holding-jaw, C. The jaw C is preferably formed of a single bar of metal provided with two arms, c, at right angles to the gripping-jaw. The ends of the 40 arms are bent at right angles to the arms, to serve as the pintles of the hinges, the sockets of which are simply the eyes in a pair of ordinary screw-eyes, eyebolts, or a pair of staples, as shown at c'.

45 On the pintles c' of the jaw C is hinged a second jaw, C'. The jaw C' is provided with a pair of arms, m, similar to the arms c of the jaw C, in the ends of which are formed eyes m', through which the pintles c' of the arms c 50 extend. The arms m are adapted to swing closely within the arms c as the jaws close. The jaws, with their arms, are preferably cast

of malleable iron, and one or both of the jaws is or are provided with knobs or projections m² on its ends, which serve both as a finish 55 and assist in giving the jaws an additional grip on the clothes.

A pair of locking pins or bars, D, are each provided with an elongated eye, d, in one of their ends, which eyes are adapted to embrace the two adjacent arms c and m of the gripping-jaws. The opposite ends of the arms c and m are provided with hooks d', which are adapted to engage pins or lugs o, formed integral with or rigidly secured to one of the 65 jaws, C. When the locking-pins D are swung at right angles to the jaws, with their hooks in the direction in which the inner jaw, C', opens, the jaws are free to open and admit the bedclothes. When the latter are placed between 70 the jaws, the pins D are swung back toward each other, acting as levers, the outer ends of the eyes d' engaging the arms of the outer jaw, C, and the opposite ends of the said eyes engaging the arms of the inner jaw, C', and forcing 75 the jaws toward each other. When the hooks d' are slipped over the pins o, the jaws are securely locked in position.

To prevent the cold air from gaining access to the feet of the person occupying the bed, an 80 apron or a shield, I, preferably of thick woolen fabric, is secured on the ends of one of the holding-jaws and extends down under the end of the mattress. In the modification shown in Fig. 3 one holding-jaw only is provided. It 85 is formed of a single piece of wire bent to form two end arms at right angles to the gripping-jaw J, the latter being projected from the plane of the arms that it may gain a better hold on the clothes by pressing them securely against 90 a panel, A. This jaw is held in closed adjustment over the clothes by means of a pair of locking-pins, D, one of which is at each end of holding-jaw C and a short distance outside thereof. Their free ends are adapted to swing 95 over the ends of the holding-jaws and lock under a hook, K, set in the base about midway between the ends of the holding-jaw.

It is evident that numerous slight changes in details of construction might be resorted to 100 without departing from the spirit of my invention; hence I would have it understood that I do not confine myself to the exact construction shown and described, but consider

myself at liberty to make such changes as fairly fall within the spirit and scope of my invention.

Having fully described my invention, what I claim as new, and desire to secure by Letters Patent, is—

1. The combination, with an elongated base adapted to be rigidly secured to the bed at the foot thereof, and supports rigidly secured to said base, of a holder-jaw, a movable holder-jaw, substantially as described, having depending arms, the latter being pivoted to the supports, and a bar engaging one of said arms for holding the movable jaw in closed adjustment, substantially as set forth.

2. In a bedclothes-holder, the combination, with a base, supports secured thereto, and a pair of swinging jaws secured to said supports, of a foot shield or apron secured between the jaws, and means for holding the jaws closed.

3. In a bedclothes-holder, the combination, with a base, supports secured thereto, and a

pair of swinging jaws secured to said supports, of a locking device adapted to engage both jaws and hold them in locked position, substantially as set forth.

4. The bedclothes-holder consisting, essentially, of a pair of jaws, one being hinged to the bed and the other being hinged to its mate, and a pair of locking-bars loosely secured on the ends of the jaws, substantially as set forth.

5. The combination, with a base, of a pair of jaws, one hinged to the bed and the other hinged to its mate, and a locking-bar having an elongated eye adapted to embrace the corresponding parts of the two jaws and force and hold them together, substantially as set forth.

In testimony whereof I have signed this 40 specification in the presence of two subscribing witnesses.

HENRY O. THOMAS.
